UNITED STATES PATENT OFFICE.

FRANCIS P. MCCOLL, OF ST. ANDREWS, NEW BRUNSWICK, CANADA, ASSIGNEE TO
AMERICAN KEY CAN COMPANY, OF CHICAGO, ILLINOIS, A CORPORATION OF
NEW JERSEY.

CAN-BODY.

1,160,188.

Specification of Letters Patent. Patented Nov. 16, 1915.

Application filed February 6, 1905. Serial No. 244,422.

To all whom it may concern:

Be it known that I, FRANCIS P. McCOLL, a citizen of the United States, residing at St. Andrews, Province of New Brunswick, 5 Dominion of Canada, have invented a certain new and useful improvement in Can-Bodies, and declare the following to be a full, clear, and exact description of the same, such as will enable others skilled in the art 10 to which it pertains to make and use the same, reference being had to the accompanying drawings, which form a part of this specification.

My invention has for its object the production of a metal can or package of the class generally known in the trade as a "roll top" can, that is one in which the "top" of the can (in some shapes what might be termed the end of the can), is soldered to 15 the body in such a manner that it may be rolled or torn off, usually by means of a key.

In this class of cans it is customary to turn from the edge of the body either inwardly 20 or outwardly (both forms are employed) a flange extending at a right angle from the body, and to this flange the flange on the top or end as the case may be, is soldered so that the latter may be torn from the body flange 25 by separating the solder.

It has been found that when light weight tin is used, the solder would not separate but instead the body flange would bend up, with the result that if the two are separated 30 at all it is only after the shape of the can has been destroyed.

My invention contemplates the strengthening of the body flange in such a way as to insure the separation of the solder when the 35 top or end is to be removed, thus making a clean, neat job of the can opening.

In the drawings, Figure 1 is a longitudinal section of a can embodying my invention. Fig. 2 shows a different form of can. Fig. 45 3 is an enlarged section of the structure shown in Fig. 1. Fig. 4 is an enlarged section of a variation.

In carrying out the invention A represents the body of the can, and B the body 50 flange, turned outwardly from the body at an angle, preferably of 90°.

C is the top or end. In Fig. 1 I have shown a round cylindrical can, so that C

represents the end. In Fig. 2 I have shown a flat or sardine can so that C represents the 55 top.

D is a flange on the top or end, adapted to be soldered to the flange B of the body.

The invention in this case resides in the formation of the flange B. In Figs. 1 and 60 2 (and shown enlarged in Fig. 3), it will be observed that this flange consists of two portions, one b integral with the body A and turned outwardly therefrom, and the other b' integral with the first and turned back 65 upon the first. When these two portions are squeezed together they form practically a single integral flange, but of double thickness so that sufficient body is provided to resist the tenacity of the solder and thus allow 70 the top flange D to be torn away from the body flange B.

In Fig. 4 I have shown a slightly different form of flange B. In this case the portion b' instead of being bent back on the portion 75 b, above the latter, is bent back below the latter.

The process of forming this latter style of flange is set forth in another concurrently pending application; and consists essentially in turning the edges of the blank before the body is formed, upon themselves 80 and then forming the body flange in the usual way after the body is formed.

By the above construction, I have obtained 85 a roll top can of the class described, in which the body flange is of sufficient strength to insure the separation of the solder when the top is removed.

What I claim is: 90
In a can of the class described, a can body having its edge bent outwardly so as to form a flange making a sharp corner with the body portion, a cover having a flange in engagement with the flange on the can body 95 and having a depressed body portion fitting closely within the end of the can, the engaging portions of said body portion of the cover and of the can body and the engaging flanges being soldered together. 100

In testimony whereof, I sign this specification in the presence of two witnesses.

FRANCIS P. MCCOLL.
